PROCESS FOR TREATMENT OF
HYDROCARBONS

Arthur D. Smith, Chicago, Ill., assignor to Jenkins Petroleum Process Company, Chicago, Ill., a corporation of Wisconsin

Application November 23, 1931, Serial No. 576,855

4 Claims. (Cl. 196—50)

The invention relates to certain improvements in the heat treatment of hydrocarbons and particularly to the heat treatment of hydrocarbons while in vaporous or substantially vaporous condition.

It is a well-known fact that hydrocarbons of relatively high boiling point and complex composition, and particularly such hydrocarbons derived from petroleum, can be "cracked" under suitable conditions of heat and pressure into hydrocarbons of lower boiling point and less complex composition, familiarly known to the trade as gasoline.

It is likewise known that the cracking rate doubles for a certain temperature increment rise over substantially the usual range of liquid phase cracking, and that such rate may be maintained in vapor phase cracking by increasing such temperature increment.

In treatment in the latter phase, instead of attempting to maintain the above mentioned cracking rate, I have found that under certain cyclic circulative conditions, where a temperature and a time factor best suited for the particular hydrocarbons under treatment are employed, hydrocarbons of low anti-knock value may be transformed into hydrocarbons of higher anti-knock rating; this especially applying to hydrocarbons of the straight chain, paraffine and/or naphthene base series having a distillation range substantially equivalent to that of naphtha or gasoline.

I do not attempt to explain whether such transformation is due to the formation of isomers of the immediately above mentioned hydrocarbon series, or to partial conversion into hydrocarbons of the benzene or "ring" series, but the fact remains that under the above described transforming treatment such conversion occurs; and that the transformed product has less tendency to "knock" or "ping" in a high compression internal combustion engine than before treatment; or possesses in the language of the trade a higher "benzole equivalent" or "octane number".

Transformation of this order is however difficult of control, and is frequently accompanied by the production of such quantities of permanent gas and/or carbon that the process is uncommercial.

A general purpose of the invention is to provide a process and apparatus for transforming hydrocarbons in vapor, or substantially vapor phase, at a temperature and under a time factor best suited to increase the anti-knock value or

"octane number" of such hydrocarbons with a minimum volumetric loss.

A corollary purpose of the invention is to effect such transforming treatment inhibitive of the production of permanent gas and/or carbon. 5

An important object of the invention is to provide a process and apparatus for the transformation of hydrocarbons of relatively low boiling point and initially low "octane number" in vapor, or substantially vapor phase, at a temperature 10 and under a time factor, whereby such hydrocarbons will be converted into low boiling point hydrocarbons of higher "octane number".

An auxiliary object of the invention is to conduct such preceding transformation on such 15 hydrocarbons obtaining as a product of a previous cracking treatment.

A further auxiliary object of the invention is to conduct such preceding transformation directly on such hydrocarbons obtaining as a vaporous or substantially vaporous product of a previous cracking treatment. 20

Another object of the invention is to provide a process and apparatus whereby hydrocarbons of comparatively high boiling point are subjected to cracking treatment; and relatively low boiling point hydrocarbons obtained thereby are treated in vapor, or substantially vapor phase, at a temperature and under a time factor best suited to increase the "octane number" of the 30 relatively low boiling point hydrocarbons so treated.

A specific object of the invention is to provide a process and apparatus for the continuous cyclic treatment of hydrocarbons in vapor, or 35 substantially vapor phase, at a temperature, and under a time factor and pressure best suited to increase the "octane number" of said hydrocarbons with an otherwise minimum change in their physical characteristics. 40

I attain the above described objectives by subjecting the hydrocarbons to be treated while in a vapor, or substantially vapor phase, to continuous cyclic circulation under a constant temperature, transforming time factor and pressure best suited to effect the desired increase in "octane number" consistent with a minimum production of by-products, such as polymerized hydrocarbons of high boiling point, permanent gas and/or carbon. 45

While the specific temperature, time factor and pressure employed will vary with the hydrocarbons processed, the temperature range will lie between 800°—1400° F. and the pressure between 0-500 lbs.; the temperature and time fac- 50
55

- tor however, being of greater importance than the pressure in controlling the percentage conversion. While a short exposure to the high temperature limit mentioned, immediately followed by a sudden reduction in temperature below that where a substantial increase in octane value is noticeable, may achieve the optimum in exceptional cases, I have found that far better results can be usually obtained by subjecting the hydrocarbons to be processed to rapid cyclic circulation at the lowest temperature where a substantial increase in "octane number" becomes apparent, and to continue to maintain such temperature during such cyclic circulation through absorption of minimum increments of heat per unit volume of cyclically circulating vapor.

While in liquid phase cracking a body of cyclically circulating oil may exist in liquid phase simultaneously and distinct from the reaction products existing in vapor phase, there is no such separation in vapor phase cracking. To effect the above mentioned cyclic circulation and at the same time maintain a constant volume flow of vapor through the cracking means, which may be preferably of multi-tubular construction, I introduce therein a circulating means, preferably a multi-bladed fan of turbo-impeller type, having a relatively large circulative ratio to a unit volume of flowing vapor; thus being able to effect within a flowing vapor stream a degree of internal cyclic circulation in proportion to the ratio between circulative and free flow volume. In other words, I dominate a continuous vapor flow through the cracking means by internal cyclic circulation, and am thus able at one and the same time, to maintain a constant temperature throughout said cracking means, a constant volume vapor flow therethrough, and to reduce the heating surface contact time per unit of circulating vapor substantially in proportion to the cyclic circulative throughput volume ratio. An important sequence of such cyclic circulative treatment is a reduction in the heating surface of the transforming means, thus effecting a substantial saving in installation cost.

After release from the cyclic transforming means, the hot, superheated vapor is conducted to a non-extraneously heated transfer drum where, through the agency of therein introduced cooling oil, preferably of relatively low octane value and substantially vaporizable at the temperature obtaining (for example, the charging stock supplied to the cyclic transforming means or crude oil), said superheated vapor is reduced to an equilibrium temperature inhibitive of the production of undesirable decomposition products, but formative of an increase in octane value of said cooling oil.

60 Polymerized hydrocarbons of relatively high boiling point formed during the reaction may be withdrawn from the transfer drum as a liquid residuum and subjected to further refining treatment, or employed as fuel, or completely removed from the system as may be desired.

The main vaporous fraction released from the transfer drum may be directly subjected separately, or admixed with a hydrocarbon of higher "octane number" than the charging stock supplied to the cyclic transforming means, to dephlegmation in a bubble tower of conventional design, with subsequent recovery therefrom of a liquid gasoline of high "octane number" and separation of permanent gas in a manner well known in the art; or the main va-

porous fraction released from the transfer drum may be preferably brought into indirect heat exchange with the charging stock supplied to the cyclic transforming means, before subjection to said dephlegmation.

The immediately above mentioned hydrocarbon of higher "octane number" may be for example, a light gasoline fraction boiling under 350° F., obtaining from a previous refining treatment; and said admixture may occur prior to or 10 after said heat exchange, and in the latter instance before or after entrance to said bubble tower; the point of admixture depending on the heat obtaining in the main vaporous fraction and the resistance of the admixed hydrocarbon to further increase in "octane number".

The bubble tower bottoms may be subjected to further transforming treatment, or employed in part as cooling oil to effect the before mentioned equilibrium temperature; or such product 20 may be further refined according to a known method, or withdrawn from the system as may be desired.

The gasoline ultimately recovered as a distillate condensate from the bubble tower, will be 25 materially higher in "octane number" than the raw material originally charged to the transforming means, the exact increase in the specific example cited depending on the chemical nature of said raw material; and in general 30 upon the physical and chemical composition of the raw stock processed, the transforming temperature, time factor and extent of the cyclic circulation employed.

As a variation of the process, a plurality of 35 the previously described cyclic transforming means, each equipped with a circulating device of the type herein mentioned, may be employed in combination with synchronously operated charging and release valves to effect a predetermined degree of recycling within one transforming means without addition of raw material thereto, or release of vapor therefrom, until said predetermined treatment has been completed; other transforming means receiving a vapor charge in such interval; said means operating in alternate or successive rotation depending upon the number of separate units employed, with the transformed vapor being ultimately released to the transfer drum and the remainder of the process conducted in the manner before described.

In order that the invention may be better understood, reference is made to the accompanying drawings in which like reference characters designate corresponding parts throughout the several views and wherein:

Figs. 1 and 2 show respectively in front and rear elevation a cyclic transforming means suitable for effecting the major increase in "octane number" herein described.

Fig. 3 is a longitudinal cross-section along the line AA of the apparatus shown in Fig. 1 as it appears positioned in a suitable furnace construction also shown in longitudinal cross-section.

Fig. 4 represents essentially in diagrammatic elevation the apparatus shown in Fig. 1, together with the previously described transfer drum, dephlegmating and condensing means; with such assembly in combination with a liquid phase cracking apparatus of known type supplying the raw material to be transformed.

Referring to the drawings, 1 is a cyclic transforming tube still, comprising an upper cross drum 2, and a lower cross drum 3, whose ends are closed by flanges 2' and 3' respectively. Into

said drums are expanded the circulating tubes 4, the latter being connected in vertical tiers at their rear ends by separate manifold headers 5, provided with clean out plugs 6.

5 Charging of the transforming means is effected through the line 7 as controlled by valve 8, which may be replaced by, or employed in conjunction with a valve of automatic operation; while the transformed product is released through line 9, 10 as controlled by valve 10, which may also be replaced by, or used in connection with an automatically operated valve. The safety valve 11 serves to relieve any excess pressure that may be developed.

15 Intermediate between, and respectively connected to the upper and lower cross drums 2 and 3 by nozzles 12, 12', 12'' and 13, 13' is the circulating means 14; said means forming with the cross drums 2 and 3, tubes 4, and manifold headers 5, a closed cyclic internal circuit.

The circulating means comprises a housing 15, enclosing a multi-bladed fan 16, rigidly mounted on a shaft 17, and driven by an electric motor 18 or other suitable source of power. The shaft 25 17 is supported by the thrust bearings 19, 19' and internal bearing 20, while the known type of oil cooled stuffing box housing 21 serves not only to effectively seal the rotating shaft 17 against the operating pressure, but lubricates the internal bearing 20 of said shaft by means of oil supplied by the ducts 22 leading from the annular cooling chamber 23, surrounding the stuffing box 24. Cooling oil is introduced to the chamber 23 through line 25 and withdrawn 35 through line 26; said cooling oil being supplied by any suitable means, such as a rotary pump, designed to operate under a pressure slightly in excess of that obtaining in the cyclic transforming means.

40 The latter assembly is mounted over a furnace of known type, comprising suspended arches 28, flue-gas ports 29, downcomers 30, return underground flue 31, and stack 32. The burners 33 are adaptable for either liquid or gaseous fuel, 45 and preferably have their fuel supply automatically controlled by a known type of thermostatic device 34, located in the release or transfer line 9.

The metal employed throughout the cyclic circuit is of heat resisting or special alloy steel suitable for the high temperatures involved, and all exterior surfaces thereof not exposed to furnace action are protected from heat loss by refractory insulation (not shown); such protection in the case of the manifold headers 5 taking the form 55 of a suitably insulated metallic housing 27, provided with doors 27' which may be opened for tube inspection or cleaning purposes. The transforming means is also equipped with the usual indicating and/or recording gauges (not shown) 60 commonly used in the art for registering temperature and pressure.

Passing to the more general aspects of the invention, and referring to Fig. 4; 35 designates a known type of liquid phase cracking still from 65 which the cracked vaporous products are conducted by the vapor line 36 to the baffle tower 37, maintained under the full still pressure, and from which tower reflux condensate is returned to said still by the reflux line 38. The partially dephlegmated crude gasoline vapor separated in said baffle tower may be conducted by line 39, with flow and pressure drop controlled by the pressure release valve 40, into the dephlegmating or bubble tower 41, with the reflux condensate or heavy 70 naphtha therefrom forming the chief source of

raw material for the transforming process herein described; or the bubble tower 41 may be eliminated, and the crude gasoline obtaining from the baffle tower 37, with control therefrom effected by valve 40', directly employed as the chief source 5 of raw material.

It is to be understood that the still 35 may be replaced by a known type of vapor phase cracking still, or a non-cracking shell, or tube still; in short, any apparatus capable of continuously 10 supplying the raw material to be transformed in vapor or substantially vaporous form, or at a temperature where such material may be readily vaporized.

In the combination herein described, I employ 15 crude gasoline or naphtha directly obtaining from the baffle tower 37 as raw material for the subsequent cyclic transforming process, where said crude gasoline or naphtha, when subjected to fractional distillation, shows the low boiling 20 fractions obtaining thereby do not differ materially in "octane number" from the intermediate or residual fractions.

Where however a distillation test indicates the low boiling fractions to be of relatively higher 25 "octane number" than the intermediate or residual fractions, I prefer to first separate the said low boiling fractions and conduct the cyclic transforming treatment on the intermediate and/or residual fractions; or in the practical application of the process, to maintain such temperature at the top of the bubble tower 41 by a suitable dry or wet trim coil, that only low boiling fractions of relatively high "octane number" escape therefrom as vapor, and the remainder of 35 the gasoline is condensed therein to form raw material for cyclic transformation.

Such raw material is withdrawn from the bubble tower 41 through the line 42, and by means of the high pressure pump 43, whose speed is preferably controlled by the float mechanism 44, is forced through line 45 (in which a flow meter 46 may be interposed), lines 47, 48, and 7, past check valve 49 and control valve 8 into the cyclic transforming means 1; with said raw material 45 being preferably preheated by passage through the heat exchanger 50 to a vaporous or substantially vaporous condition.

Crude gasoline or naphtha vapor obtaining directly from the baffle tower 37, when employed as 50 raw material is conducted through line 39, as controlled by valve 40', through line 47 and thence to the cyclic transforming means as above described; the pressure in the baffle tower 37 being usually sufficient to force the vapor directly into 55 the transforming means under the pressure there obtaining without interposed compression means, which however may be employed where necessary.

Converted vapor is released from the cyclic transforming means 1 through the line 9, as controlled by valve 10, to enter the transfer drum 51, where said vapor is cooled by contact with a relatively cold hydrocarbon, to the previously described equilibrium temperature, said cooling hydrocarbon being introduced into said drum through the line 52 terminating in the perforated spray coil 52'.

The cooling hydrocarbon may be a fractional portion of the raw material flowing through line 47, diverted therefrom through the branch line 70 53, as controlled by valve 53' connecting to said line 52. An interposed cooling means 54 serves to lower the temperature of the cooling hydrocarbon if such be desirable. The cooling hydrocarbon may be a condensate from the bubble tower 55, 75

with flow therefrom effected through lines 56 and 56', as controlled by valves 57, 58 and 58'; pump 59 being employed to force said condensate through line 60, as controlled by valve 61, to said line 52 and thus entering transfer drum 51. A cooling means 62 may be interposed in line 60, operative in the manner above described, and additional or other cooling hydrocarbon such as crude oil for example, may be supplied to transfer drum 51 by a source without the system through line 63, as controlled by valve 57', feeding pump 59. It is to be understood that any mixture of the cooling hydrocarbons herein mentioned may be employed under suitable valve manipulation in a manner that will be apparent to one skilled in the art. Condensate from tower 55 may be withdrawn through cooling coil 64, as controlled by valve 58', and removed from the system; or such condensate, controlled by valve 58, may be forced by pump 65 through line 66 to the baffle tower 37.

Balanced valves (not shown) may be installed in lines 56' and 63, operated by suitable float mechanisms in connection with the bubble tower 55, so that a constant liquid level will obtain therein, and at the same time an adequate quantity of cooling hydrocarbon will be supplied to pump 59.

Liquid residuum is discharged from the transfer drum 51 through line 67, and may be withdrawn from the system through cooling coil 68 as controlled by valve 69; or such residuum may be forced by pump 70 as controlled by valve 69' through line 71 to baffle tower 37.

Transformed vapor obtaining in transfer drum 51, cooled to the equilibrium temperature herein mentioned, is released through lines 72 and 74, as controlled by valves 73 and 73', through heat exchanger housing 50', to effect indirect heat exchange with the raw material (which if not already in vaporous condition attains such phase in such heat transfer), and then enters the bubble tower 55 through line 75; the control valves 73, 73' permitting by-passing of the transformed vapor in any desired degree direct to said bubble tower 55.

Relatively high "octane number" gasoline vapor escaping from bubble tower 41 through line 76, as controlled by valve 76', may be conducted through lines 77 and 7, as controlled by valve 98 and check valve 98', and thence forced by compressor 99 to the cyclic transforming means 1; or said gasoline vapor may be conducted through line 77 as controlled by valves 78, 78', to the condenser 79 and thence to accumulating drum 80, where permanent gas is released through line 81, as controlled by relief valve 81' set at a predetermined pressure. Liquid gasoline may be withdrawn from the system through line 82, as controlled by valve 82', or such gasoline may flow through line 83, as controlled by valve 83', to pump 84, and be thence delivered through lines 85 and 86 as controlled by valves 87 and 87' to the bubble tower 41 as a trim; or such gasoline may be employed wholly or in part as a liquid trim for bubble tower 55, discharging thereto through lines 85 and 88, as controlled by valves 87, 89" and 89'.

In lieu of the above practice the gasoline vapor of high "octane number" from bubble tower 41 may be conducted through line 77 as controlled by valves 90, 90' to line 75 and commingle with the vapor obtaining from transfer drum 51 before introduction into the bubble tower 55; or with a different adjustment of said valves 90, 90' said

gasoline vapor, commingled with high "octane number" gasoline vapor escaping from bubble tower 55 through line 91 as controlled by valve 91', may be condensed in condenser 92 and the condensate therefrom conducted to accumulating drum 93, where permanent gas is released through line 94 as controlled by valve 94' set at a predetermined pressure. Liquid transformed gasoline of high "octane number" may be withdrawn from the system from said drum 93 through line 95 as controlled by valve 95', or a portion of such gasoline may flow through line 96 as controlled by valve 96', to pump 97; and thence be delivered through line 85' as trim stock to bubble towers 55 or 41, under the respective control of valves 89, 89' and 87", 87'.

The immediately above described connections permit a wide latitude in the application of relatively high "octane number" trim stocks and the blending of similar vapors, for it has been discovered that under selective blending of such trim stocks and vapor admixtures of the order, and in their application herein described, the final transformed gasoline as withdrawn from the system is of higher "octane number" than a simple mixture of like proportions of independently condensed gasoline obtaining under respective cyclic transforming and liquid phase treatment. Such result is attained in the combination herein described, sometimes with the major portion of the aforesaid trim stocks fed to the liquid phase bubble tower, and at other times to the transforming means bubble tower; the effect being seemingly dependent on the nature of the raw and intermediate materials, temperatures and time factors employed in the process steps, and to a less extent on the pressure involved.

The invention is not limited in its process application to the type or arrangement of the instrumentalities herein described; nor are such instrumentalities as are herein claimed limited to any one process, nor to the precise form and relational size between parts as indicated by the drawings; and what I claim is new and desire to protect by Letters Patent is:

1. A process for increasing the octane number of hydrocarbon vapors which comprises conducting said vapors to a dephlegmating zone and therein separating out heavier fractions as a condensate leaving in vapor form desired light fractions, conducting a portion of said condensate of heavier fractions to a vaporizing zone and therein substantially revaporizing said condensate, subjecting the revaporized condensate to vapor phase cracking by cyclically circulating it through a heated, closed ring, continuously withdrawing a portion of the products of such vapor phase cracking reaction relatively small in proportion to the volume under cyclic treatment, continuously replacing such withdrawn portion by additional revaporized condensate, immediately commingling the withdrawn portion with hydrocarbon oils at a lower temperature to reduce the temperature of said withdrawn portion to a temperature preventive of the formation of free carbon, separating vapors from the resultant mixture, and passing said vapors in indirect heat interchange with said condensate of heavier fractions in said vaporizing zone to substantially revaporize said condensate as aforesaid.

2. A process for increasing the octane number of hydrocarbon vapors which comprises subjecting hydrocarbon oils to a cracking reaction under pressure in liquid-vapor phase to evolve vapors therefrom separating and removing vapors so

evolved to a fractionating zone and therein condensing out a heavy condensate portion, conducting the remaining vapors to a dephlegmating zone and therein separating out heavier fractions from said vapors as a condensate, removing a portion of the condensate thus formed to a vaporizing zone and therein substantially revaporizing said condensate, subjecting the revaporized condensate to vapor phase cracking by cyclicly 5 circulating it through a heated, closed ring, continuously withdrawing a portion of the products of such vapor phase cracking reaction while continuing to impose said cyclic cracking conditions on the remaining portion, continuously replacing such withdrawn portion by additional revaporized condensate, immediately commingling the withdrawn portion with hydrocarbon oils at a sufficiently low temperature to inhibit formation of free carbon, separating vapors from the 10 resultant mixture, and passing said vapors in indirect heat interchange with said condensate of heavier fractions in said vaporizing zone to substantially revaporize said condensate as aforesaid.

25 3. A process for increasing the octane number of hydrocarbon vapors which comprises subjecting hydrocarbon oils to a cracking reaction under pressure in the liquid-vapor phase to evolve vapors therefrom, separating and removing vapors so evolved to a fractionating zone and therein condensing out a heavy condensate portion, conducting the remaining vapors to a dephlegmating zone and therein separating out heavier fractions from said vapors as a condensate leaving in the vapor state gasoline vapors formed in the liquid-vapor phase cracking reaction, subjecting a portion of said gasoline vapors to cracking conditions in vapor phase, directly introducing the products of said vapor 30 phase cracking reaction into a zone of lower

pressure, immediately commingling therewith a portion of said condensate of heavier fractions to reduce the temperature of the products of said vapor phase cracking reaction sufficiently to prevent formation of free carbon, and fractionating 5 the mixture of oil products thus formed to obtain gasoline vapors of high octane number and heavier liquid condensates.

4. A process for increasing the octane number of hydrocarbon vapors which comprises subjecting hydrocarbon oils to a cracking reaction under pressure in liquid-vapor phase to evolve vapors therefrom, separating and removing vapors so evolved to a fractionating zone and therein condensing out a heavy condensate portion, conducting the remaining vapors to a dephlegmating zone and therein separating out heavier fractions from said vapors as a condensate, removing a portion of the condensate thus formed to a vaporizing zone and therein substantially revaporizing said condensate, subjecting the revaporized condensate to vapor phase cracking by cyclicly circulating it through a heated, closed ring, continuously withdrawing a portion of the products of such vapor phase cracking reaction while continuing to impose said cyclic cracking conditions on the remaining portion, continuously replacing such withdrawn portion by additional revaporized condensate, immediately commingling the withdrawn portion with hydrocarbon 15 oils at a sufficiently low temperature to inhibit formation of free carbon, fractionating the resultant mixture to obtain gasoline vapors of high octane number and heavier liquid condensates, and introducing said heavier liquid 20 condensates into the hydrocarbon oils subjected to said cracking reaction in the liquid-vapor phase.

ARTHUR D. SMITH. 40
